UNITED STATES PATENT OFFICE

109,772

DESIGN FOR A PAIR OF SPECTACLES

Edward M. Splaine, Southbridge, Mass., assignor
to American Optical Company, Southbridge,
Mass., a voluntary association of Massachusetts

Application October 18, 1937, Serial No. 72,246

Term of patent 14 years

To all whom it may concern:

Be it known that I, Edward M. Splaine, a citizen
of the United States of America, residing at
Southbridge, in the county of Worcester and
State of Massachusetts, have invented a new,
original, and ornamental Design for a Pair of
Spectacles, of which the following is a specification,
reference being made to the accompanying
drawing forming a part thereof.

Fig. I is an enlarged perspective view of a pair
of spectacles showing the dominant feature of my
design in full lines;

Fig. II is an enlarged fragmentary front view
of the spectacles shown in Fig. I;

Fig. III is an enlarged fragmentary top or plan
view of Fig. I; and

Fig. IV is an enlarged fragmentary perspective
view of Fig. I.

The dominant feature of the present design is
shown in solid lines in the drawing and com-
prises an arm which is blended at its forward
end with the lens connection and which extends
rearwardly and outwardly from said lens con-
nection and has a temple connection adjacent
its outer end.

The forward end of the temple, the arm and
the lens connection are all provided with con-
tinuously blended outer surfaces and sweeping
curved contours which join in flush relation with
each other and without abrupt or sharp interrup-
tions.

I claim:

The ornamental design for a pair of spectacles,
substantially as shown and described.

EDWARD M. SPLAINE.
